UNITED STATES PATENT OFFICE.

ALBERT J. ASHER AND WILLIAM A. GAUTT, OF ROUND ROCK, TEXAS.

CAR-COUPING.

SPECIFICATION forming part of Letters Patent No. 650,523, dated May 29, 1900.

Application filed June 30, 1899. Serial No. 722,357. (No model.)

To all whom it may concern:

Be it known that we, ALBERT J. ASHER and WILLIAM A. GAUTT, citizens of the United States, residing at Round Rock, in the county 5 of Williamson and State of Texas, have invented a new and useful Car-Coupling, of which the following is a specification.

This invention relates to car-couplings of that class embodying a pair of pivoted catches 10 engaging a headed link and having suitable uncoupling-levers therefor.

The objects of the present invention are to provide certain new and useful improvements in this class of couplings which will greatly 15 simplify the construction and facilitate the operation thereof by providing levers upon the end of the car having suitable connections with the pivoted catches, whereby the device may be operated, and, further, to provide 20 vide means for locking the levers to hold the coupling open. These and other objects and advantages of our improvements will be hereinafter more fully described, shown in the drawings, and particularly pointed out in the 25 claims.

In the drawings, Figure 1 is a perspective view of the end of a car having our improvements applied thereto. Fig. 2 is a top plan view of the coupler having the top of the 30 draw-head removed. Fig. 3 is a vertical longitudinal sectional view thereof. Fig. 4 is a detail view illustrating the manner of locking the levers. Fig. 5 is a detail perspective view of one of the pivoted catches. Fig. 6 is a detail perspective view of the headed link. 35

Corresponding parts in the several figures are denoted by like characters of reference.

Referring to the drawings, 1 designates the 40 end of a car having our improvements attached thereto. The draw-head 2 is connected with the car in the usual manner. Arranged within the mouth of the draw-head and pivoted at each side, as at 3, is a pair of jaws or catches 4. These catches are pivoted at or near the outer end of the draw-head, extending therein a suitable distance, being beveled at its inner end, as at 5, and provided with a longitudinal slot or groove 6 in the upper edge thereof. These pivoted catches or 45 jaws are operated by means of oscillating levers 7, which comprise vertical shafts 8, journaled in the draw-head and having the hori-

zontal arms 10 and 11 arranged at each end, respectively, and projecting in opposite directions, as clearly shown in Fig. 3. The extremities of the lower arms 10 are bent at an angle, as at 9, and operate in the slots 6 of the jaws. The arm 11 of lever 7 extends above the top of the draw-head and is formed into a hook 12, which is suitably secured to 55 rods 13 and 14, forming connection with the operating-levers 15. These levers 15 are pivoted to the end of the car, at or near the lower end thereof, and at each side of the draw-head, having the operating-handle 16 of one lever 60 65 extending above the top of the car and the other below the bottom of the car, so that they may be operated both from the ground and from the top of the car. Each of the levers 7 has a connection with each of the operating-levers 15 by means of the short rod 13, connecting with the short arm of one of the levers 15, and the long rod 14 with the long arm of the other lever 15. By this arrangement it will be readily understood that 70 75 the device may be operated to couple or uncouple from either side of the car. A suitable spring is connected with one of the levers to hold the device in coupled position, shown here as a coiled spring 16, fastened 80 to the end of the car at one end and to the lever 15 at the other.

To accommodate this coupler to the ordinary pin-and-link coupling, we provide a suitable pin 17, connected to the end of the 85 car by a chain 18 and adapted to enter alined openings 19, provided through the top and bottom of the draw-head.

It is sometimes necessary to hold the pivoted jaws 4 open, as when coupled to the ordinary pin-and-link coupling, and we have provided means therefor, comprising a latch 20, pivoted at one end upon the top of the car and formed into a transverse head or stop-shoulder 21 at the other end and having a 90 guide 22, fastened over the latch to limit the movement thereof and hold the same always in a convenient position for operation. To lock the levers, it is simply necessary to draw either one of them outward and throw the 100 head of the latch into a notch 23, provided upon the inner face of the lever, as shown in Fig. 4, when the device is effectually locked in open position. A similar arrangement is

provided upon the under side of the car for the lower lever 15.

The form of link used in connection with our coupler is shown in Fig. 6 and comprises a bar 24, having an arrow-head 25 at each end, forming the draft-shoulders 26, and provided with a stem or shoulder 27 midway between the ends of the bar, extending below and at each side thereof to form a stop limiting the inward movement of the link, and the lower side of the mouth of the draw-head is cut away or curved, as at 28, to form a seat for the stem 27, which normally extends downward.

15 Our improvements provide a simple and durable car-coupling having efficient means for uncoupling both from the top of the car and from the ground, thus obviating the necessity of going between the cars, and protects the trainmen from the dangers consequent with the ordinary pin-and-link coupler.

Changes in the form, proportion, and minor details of our improvements may be made without departing from the spirit and scope 25 or sacrificing any of the advantages of our invention, and we therefore do not wish to be understood as limiting ourselves to the precise construction as herein described, and shown in the drawings.

30 Having thus described the invention, what is claimed, and desired to be secured by Letters Patent, is—

1. In a car-coupling, the combination with a pair of jaws pivoted within the draw-head, 35 of a pair of operating-levers arranged respectively at opposite sides of the draw-head, and fulcrumed intermediate their ends, and rods operatively connected respectively with said jaws and the two arms of their respective levers, substantially as described.

2. In a car-coupling, the combination with a pair of jaws pivotally mounted in the draw-head, of an intermediately-fulcrumed operating-lever mounted at one side of the draw-head, and a pair of oscillating levers each having a sliding engagement with one of the

jaws and having their opposite ends connected respectively to the two arms of the operating-lever, substantially as described.

3. In a car-coupling, the combination with 50 a pair of jaws pivoted within the draw-head, and a pair of operating-levers mounted upon the end of the car and arranged respectively at opposite sides of the draw-head, of means operatively connecting the respective jaws 55 and the levers, comprising an oscillating lever pivoted through the top of the draw-head, having one end working in a slot or groove formed in the upper edge of the jaw, and rods connecting the other end of the oscillating 60 lever, with each of the operating-levers, substantially as shown and described.

4. In a car-coupling, the combination with a pair of jaws pivoted within the draw-head and a pair of operating-levers mounted upon 65 the end of the car, being arranged respectively on opposite sides of the draw-head, and having the handles of the respective levers extending one above and the other below the car, of means operatively connecting the respective jaws with each of the levers, comprising an oscillating lever pivoted through the top of the draw-head, having one end working in a slot or groove formed in the upper edge of the jaw, rods connecting the other 70 end of the oscillating lever with each of the operating-levers at points on opposite sides of the pivots thereof, a spring connected with one of the levers for holding the jaws in locked position, and a latch pivoted upon the 75 car having a head or shoulder engaging a notch in one of the levers, for holding the jaws in open position, substantially as shown and described.

In testimony that we claim the foregoing as 80 our own we have hereto affixed our signatures in the presence of two witnesses.

ALBERT J. ASHER.
WILLIAM A. GAUTT.
